[57] **CLAIM**

The ornamental design for a holder for empty cassette case, as shown.

DESCRIPTION

FIG. 1 is a front elevational view of a holder for empty cassette case showing my new design;

FIG. 2 is a top plan view thereof;

FIG. 3 is a bottom plan view thereof;

FIG. 4 is a rear elevational view thereof;

FIG. 5 is a left side elevational view, the right side elevational view being a mirror image thereof; and

FIG. 6 is a reduced-scale perspective view thereof.

FIG. 6-

FIG. 1-

FIG. 2-

FIG. 3-

FIG. 4-

FIG. 5-
